3 Claims. (Cl. 61—45)

The present invention relates to sliding bearer-sets for mine galleries, said bearer-sets being made up preferably of channel sections which fit one inside the other, and is more especially concerned with sets which are made up of a head-piece (socket section) and two uprights (inserted sections) which are joined together in each overlapping zone by a top assembly and bottom assembly and permit of sliding movement under the action of increasing stresses exerted by the ground, at least one of said assemblies being adapted in accordance with present design requirements to be rigidly fixed in sliding motion to one of the elements of the set.

The overlapping portion, the length of which is initially in the vicinity of 40 cm., progressively increases until the extremity of each upright reaches substantially the summit of the head-piece when in the end position which corresponds to the maximum roof-subsidence, and the primary object of the invention is to permit such subsidence without producing any deformation of the constituent elements.

In point of fact, such a result has never yet been achieved and proof of this well be found from close examination of the behaviour of the upright and of the head-piece during the subsiding movement of the set. The upright performs a pivotal movement about its point of support on the ground while the upper terminal portion thereof remains in contact with the head-piece, whereas the head-piece carries out a vertical movement of translation movement of translation, thereby creating a progressively increasing gap between the end of said head-piece and the upright member.

In the case in which the assemblies are completely independent of the structural members which they join together, said structural members accordingly take up positions in which the deformations to which the sets are subjected are of minimum value, that is to say, of course, insofar as friction forces and ground obstacles permit.

In the case in which each assembly remains integral with one of the elements of the set, these latter are necessarily subjected to deformation and it is difficult to determine whether such deformation is either elastic or permanent. Permanent deformation is not admissible, whereas elastic deformation must reach a value such that the set is locked in position and any sliding movement thus becomes impossible.

It has already been proposed to overcome this disadvantage by providing the head-piece with an articulation at the central point thereof, but the increase in the cost price makes this solution commercially unacceptable.

The present invention obviates these drawbacks and accordingly arises from the following statement:

Consideration being given to a head-piece and to an upright member the upper terminal portion of which, in accordance with conventional design, has a radius of greater length than that of the head-piece in the position occupied by these members when the set is in a condition of maximum subsidence, it will be observed as previously noted that the lower extremity of the head-piece is located at a certain distance away from the upright or, in other words, forms a gap with respect to said upright.

2

Consequently if, instead of endowing the head-piece with the usual circular shape having a radius of curvature which is smaller than that of the upright, said head-piece were provided on each side of its central point with a curvature which is identical to that of the upper terminal portion of the upright and the shape of which is such that said head-piece coincides with said portion in the position above noted, the problem would accordingly be solved.

10 The object of the present invention is therefore to provide a support frame or so-called bearer-set which is formed in known manner by a head-piece and two uprights wherein said head-piece comprises two arms having a radius of curvature which is identical to the radius 15 of curvature of the respective upper terminal portion of each of the two uprights and the adjoining extremities of the said arms make the same angle with each other as the angle defined by imaginary tangential lines drawn to the two closest points on each terminal portion in the 20 position of maximum subsidence which is contemplated.

Accordingly, when the maximum subsidence which is contemplated coincides with the position in which the extremities of the uprights are in contact, the head-piece 25 then takes the shape of a perfect Gothic arch or pointed arch, whereas in the case in which the maximum subsidence contemplated does not reach the point of contact of the extremities of the uprights, the two arcuate arms of the head-piece are rigidly coupled together by a central arm. In both cases the head-piece is constructed in 30 such a manner that the origins of the radius of curvature of the two arms do not coincide. In other words, the two arms of the head-piece do not lie on a single imaginary circle.

The operation involving the formation of one or two 35 angular points in a head-piece of conventional shape can readily be performed by press-work and is very advantageous from the point of view of cost price; furthermore, the small amplitude of the angle of deformation which is imparted to the head-piece is not liable to subject the metal to unacceptable stresses. Finally, it will 40 be noted that the pointed-arch shape has a higher crushing strength than the circular shape.

The invention will be more clearly understood by reference to the accompanying drawings, in which:

45 FIG. 1 represents the two end positions which are successively taken up by the elements of a conventional bearer-set, the head-piece of which has a radius of curvature which is shorter than that of the uprights.

FIG. 2 is a similar view of a form of embodiment of 50 a bearer-set in accordance with the invention in the two end positions thereof, the position of maximum subsidence being coincident with the point of contact of the ends of the uprights.

FIG. 3 is a similar view of a second form of embodiment in which the extremities of the two uprights do not 55 come into contact in the position of maximum subsidence.

Reference being made to FIG. 1, P designates each of the uprights of a bearer-set of the usual type and C designates the associated head-piece having a radius of curvature which is shorter than that of the uprights.

The solid outline which has a wider development shows the initial position of the elements of the set wherein the overlapping portion AB of the head-piece and of the upright has a length of the order of 40 cm. The broken outline represents the end position which is taken up by 60 the elements of the set to which there has in this case been assigned the index 1, after a sliding movement has been carried out under the action of stresses exerted by the ground (or roof).

70 In order to reach this position, the two uprights carry out respectively about their points O1, O2 of support

on the floor a movement of rotation P-P₁ whereas the headpiece carries out a translational movement C-C₁. It will be noticed that a gap is formed in this position between the ends B₁ and each upright. It should be pointed out that, if the radius of curvature adopted for the head-piece had been identical with that of the upright member, this gap would have been ever further increased whereas in the initial position, a smaller although nevertheless appreciable gap would have existed.

In accordance with the invention, the head-piece CO takes the shape of a Gothic or pointed arch (as shown in FIG. 2), the two halves of which, as constituted by sections of circular configuration and having the same curvature as the upper terminal portion of the uprights, make an angle α with each other at the central point M of the head-piece, said angle α being equal to the angle made by the two extremities A of the uprights when these latter meet at A₁ in the end positions thereof.

As has been explained in the foregoing, this shape can very easily be obtained by press-work using a head-piece of conventional configuration, without subjecting the metal to any excessive stresses and without resulting in any appreciable increase in the cost price.

It accordingly follows that, if one considers a resilient set having vertical props and a radius of curvature of 2.5 metres which is common to the head-piece and to the uprights, the angle α at the summit of the two halves of the pointed arch is of the order of 165°.

In the form of embodiment of FIG. 3 in which the two uprights P do not come into contact in the position P₁ of maximum subsidence, the head-piece CO is composed of two arms DB having the same radius of curvature as the uprights and joined together by a central arm DD of any suitable shape. As in the previously described embodiment, the two arms are disposed with respect to one another as to form a pointed arch except that in this embodiment the arch is unfinished and the truncated extremities are joined by means of the arm DD.

It thus applies to both embodiments shown in FIGS. 2 and 3 that the angle between two imaginary lines drawn tangentially to the adjacent end points on each arched arm is less than 180°. In the embodiment shown in FIG. 2 the two points practically coincide at M, while in FIG. 3 the two points are spaced and are disposed at D-D. The aforesaid angle is equal to an angle formed by two

imaginary lines drawn tangentially to the adjacent end points on each terminal portion when the head-piece is in its lowest position. In FIG. 2 the last-named two points practically coincide at A, while in FIG. 3 the two points are spaced and disposed at A₂-A₂.

What I claim is:

1. A bearer set for mine galleries comprising, two uprights of substantially the same configuration secured at their lower end to spaced points adjacent on the ground and swingable thereabout, said uprights being symmetrically disposed about an axis normal to the ground, each upright including a curved upper terminal portion, a head-piece including a pair of members rigidly secured to one another in an end-to-end and symmetrical relationship, each of said members including an arched arm slidably secured to said terminal portion of said uprights and adapted to overlap therewith, said head-piece adapted to move in a substantially linear, vertical path between a highest position and a lowest position as said uprights swing towards each other, said upper terminal portions having a radius of curvature identical to that of said arched arms adapted to overlap with said upper terminal portions, the origins of the radius of curvature of said arched arms being spaced from one another, the angle between two imaginary lines drawn tangentially to adjacent end points on each said arched arm being less than 180° and being equal to the angle formed by two imaginary lines drawn tangentially to adjacent end points on each said terminal portion when said head-piece is in its lowest position.

2. A bearer set as defined in claim 1, wherein said arms are disposed in an end-to-end relationship.

3. A bearer set as defined in claim 1, wherein said arms are rigidly linked together by means of an interconnecting member.
